UNITED STATES PATENT OFFICE.

PILADE BARDUCCI, OF NAPLES, ITALY.

PRESS FOR PASTY MATERIALS.

1,426,244.

Specification of Letters Patent. Patented Aug. 15, 1922.

Application filed January 19, 1920. Serial No. 352,265.

To all whom it may concern:

Be it known that I, PILADE BARDUCCI, a subject of the King of Italy, and resident of Naples, Italy, have invented certain new and 5 useful Improvements in Presses for Pasty Materials, of which the following is a specification.

This invention relates to presses used for drawing pasty materials, as alimentary 10 pastes, macaroni or the like, of the type comprising a cylinder in which is exerted the pressure and which is connected directly with a main conical receiver, this latter being connected in turn with a number of 15 conical die chambers each spreading towards the plane at which is located the die plate.

By a press according to this invention the output of the machine is largely increased 20 as compared to that of presses with a single main receiver provided with a die plate having the same diameter as said receiver, because owing to increased number of die plates and increased drawing surface, it is 25 possible to increase the speed of the pressing member without increasing the drawing speed of the paste through said dies. This drawing speed, in the case of alimentary pastes, must not exceed given values in order 30 to prevent the material from being injured.

This invention also comprises heating means located within the main conical receiver, as well as the construction of the 35 conical die chambers which permits taking the machine to pieces in an easy and quick manner for cleaning the same, and of replacing said die chambers. The machine may thus be arranged to operate either with a number of die plates arranged in a vertical 40 plane (as is useful for drawing short alimentary pastes) or with said die plates arranged in a horizontal plane (as required for drawing long alimentary pastes) or finally with a number of said die plates arranged in a horizontal plane and another 45 number of the same arranged in a vertical plane.

The accompanying drawings show by way of example, a construction of a press according to this invention and Figure 1 is a plan view of a half of a machine adapted to feed a number of die chambers arranged vertically and having their die plates located in a horizontal plane; Figure 2 is the 50 like view of a machine having a number of die chambers arranged horizontally and

adapted to be replaced with other ones intended to be located vertically. In both figures the cylinder arranged above the main receiver and the heating means located within said receiver have been omitted for sake of clearness. Figure 3 is the vertical section on line A—B, Figure 1, said cylinder and heating means being shown. Figure 3^A shows a modification of the heating means. 60 Figure 4 is the section on line C—D of Figure 2 with the addition of the cylinder. Figure 5 is the transverse section of a conical die chamber adapted to be arranged horizontally said section being made on line 65 E—F of Figure 2; Figure 6 is the front view of a member carrying the connecting rods for a vertical die chamber and Figure 7 is the plan view of the same; Figure 8 shows the head of a vertical conical die chamber; 70 Figure 9 is a fragmentary outer view of a press in which the position of main parts has been modified.

As shown by Figures 1, 2, 3 and 4, the press comprises a block 1 provided with 80 sleeves 1' in which are inserted the columns or pillars 2, and a cylinder 3 mounted to rotate around one of said pillars, said cylinder being thus adapted to be carried above and in register with said block and to be removed therefrom.

Said block 1 is provided with a central recess or chamber 5 which is shaped like a cone and has its larger mouth in register with mouth of cylinder 3. In the wall of 90 said block and around said chamber 5 are provided ducts or passages 4 which are intended for the passage of a hot fluid as water or steam for the purpose of heating the material contained within said chamber. 95

Within said chamber 5 is located a pear-like box 6 (see Figure 3) in which the same heating fluid is caused to circulate, said fluid being supplied and exhausted through passages 7' and 7'' provided in a stem 7 depending from said box 6 and passing through the restricted mouth of chamber 5; said stem 7 is connected by means of a sleeve 9 with a pipe 8 having passages corresponding with passages 7' and 7'' of stem 7 and 105 connected with the fluid piping. As shown by Figure 3 said stem 7 is provided with a plug 10 seating in said restricted mouth of chamber 5 and closing the passage 11 of block 1 through which is inserted said 110 stem 7.

The box 6 is further provided with wings

6' bearing against the inner surface of chamber 5 and the same box is held in the required position by said wings 6' and plug 10, a thin annular passage being left between said box 6 and the surface of chamber 5. The material is thus caused to pass between said parts in a thin layer and is thus evenly heated before reaching the die plate and therefore no means are required for 10 heating said die plate. Further, owing to the shape of said chamber and box no recess is produced in which material may lodge and spoil succeeding batches of the same.

Instead of heating the conical chamber 5 15 and the box 6 by circulation of a fluid as water or steam, the same may be heated by any other known and proper means. By way of example said heating may be obtained as shown in Fig. 3^A by means of 20 electric resistances 61 suitably arranged in the spaces provided within box 6 and for this purpose box 6 may be made of two or more parts and the conductors feeding the current may be located within passages 7' 25 and 7'', a proper connecting plug being provided instead of connecting sleeve 9.

From the bottom of chamber 5 lead passages 12 each communicating with one of the die chambers as hereinafter described.

30 As hereinbefore described said die chambers may be made so as to be mounted either horizontally or vertically and the method of connecting the same with block 1 is hereinafter described in connection with 35 both cases.

In the case of chambers intended to be mounted vertically and with their die plates located horizontally, as shown by Figures 1 and 3, each chamber is provided 40 at its restricted head 29 with an elbow duct 28 intended to come in register with a pipe 19 leading to passage 12 and seating in recesses encircling the mouths of passage 12 and of duct 28 and said head is provided 45 with lugs 30 adapted to slide on rods 14 secured to block 1. On said rods 14 there is further mounted a transverse bar 15 in which is located a screwthreaded nut 16 and a screwthreaded spindle 17 is engaged in 50 said nut 16. The enlarged end 17' of said spindle is seated in a recess provided on said head 29 and is engaged with the same by means of a collar 18 secured to said head 29 and passed through by spindle 17. By 55 operating said spindle 17, say by means of its square end 17'', the head 29 and pipe 19 are forced against each other and against the mouth of passage 12 so as to form a continuous path for the material issuing 60 from passage 12 which is thus carried into the hollow of chamber 13.

Figures 2, 4 and 5 show the mounting of 65 chambers 13' intended to be located with their axis horizontal. In this case the restricted end of each chamber is seated

directly at the mouth of passage 12 of block 1 and the same is secured to block 1 by means of bolts 20 and nuts 21, the lugs 22 integral with chamber 13' being inserted on said bolts 20.

The construction shown in connection with horizontal die chambers permits replacing the same with vertical die chambers for the purpose of utilizing the machine in the preferred or required manner.

This may be obtained by the arrangement shown by Figures 6 and 7, comprising a yoke 23 having holes 23' intended to be inserted on bolts 20 and secured thereon by means of nuts 21. Said yoke is provided with perpendicular rods 14 intended to carry the die chamber 13 and the transverse bar 15 with associate parts as described in connection with Figures 1 and 3. When mounting a vertical die chamber 13 in place 80 of a horizontal one 13' a pipe 19 must be located between the mouths of passage 12 and of restricted opening 28 of said chamber as before described.

Means are provided for securing the die 90 plate 24 at the larger mouth of the die chamber, said means consisting, by way of example, of a sleeve 25 adapted to be screwed on the mouth of said chamber and having a flange 25' engaging the edge of 95 said die plate 24, as shown by Figure 3.

Chamber 13' and sleeve 25 may also be provided with means for supporting said sleeve when it is removed from the chamber mouth for the purpose of changing the die 100 plate. Such an arrangement is shown, by way of example, in Figures 2, 4 and 5. In this case the chamber 13' is provided with projections 31 having holes 32 adapted to receive rods 27 on which is slidably mounted 105 a ring 26 engaging a groove of sleeve 25 so as to allow said sleeve 25 to be rotated for screwing and unscrewing the same on and from the mouth of chamber 13' but preventing said sleeve from moving in a 110 transverse direction with regard to the axis of said rods 27 and chamber 13'.

Said arrangement for supporting sleeve 25 has been described and illustrated in connection with horizontal die chambers shown in 115 Figures 2 and 4 but it is to be understood that the same may also be used in the case of vertical die chambers; in this case this arrangement may also comprise rods adapted to slide through lugs projecting from chamber 13 said ring 26 being secured to said rods and engaging sleeve 25 in a rotatable manner.

The described construction permits an 120 easy and quick disassembling of the machine for by unscrewing sleeve 9 the pear box 6 may be removed from chamber 5 and by unscrewing sleeves 25 the die plates 24 may be removed from their chambers 13 or 13'; then the die chambers may be removed by un- 125 130

screwing nuts 21 or by releasing spindles 17 and rods 15 and thus also pipes 19 may be removed.

It is to be understood that the relative position of the several parts of the press may be reversed as shown by way of example by figure 9 in which the cylinder 13 is located under the block 1, this latter being reversed with regard to position shown in other figures of the drawing and the die chamber 13 being connected with the upper restricted end of the chamber provided in said block.

In this case the piston or other member producing a pressure within cylinder 3 operates by rising instead of being lowered within said cylinder as in the case of Figures 1, 2, 3 and 4.

What I claim as my invention and desire to secure by United States Letters Patent 20 is:—

1. In a press for drawing pasty materials, the combination with a block having a conical main chamber and a plurality of exhaust passages; of a plurality of conical secondary chambers; and sets of rods, each set being adjacent one of said passages and carrying one of said secondary chambers.

2. In a press for drawing pasty materials, the combination with a block having a conical main chamber and a plurality of exhaust passages; of a plurality of secondary conical chambers; a plurality of sets of rods, each

set being adjacent one of said passages and carrying one of said secondary chambers; and removable sleeves each for connecting 35 one of the passages of the main chamber with the registering secondary chamber.

3. In a press for drawing pasty materials, the combination of a block having a conical main chamber and secondary chambers connected with said block; and a heating member 40 removably mounted in the central portion of said main chamber.

4. In a press for drawing pasty materials, the combination of a block having a conical 45 main chamber and secondary chambers connected with said block; and a speroidal member removably mounted in the central portion of said main chamber and means for heating said member.

5. In a press for drawing pasty materials, the combination of a block having a conical main chamber and a central passage; a plurality of secondary chambers connected with said block; and a member located in the 55 central portion of said main chamber and having a depending stem seated in said central passage of said main chamber, said stem being provided with means feeding a heating medium in said member.

Signed at Naples, Italy, this 8th day of December, A. D. 1919.

PILADE BARDUCCI.
